UNITED STATES PATENT OFFICE.

THOMAS G. NEWNAM, OF HOLDEN, MISSOURI.

WASHING-MACHINE.

SPECIFICATION forming part of Letters Patent No. 328,801, dated October 20, 1885.

Application filed April 9, 1885. Serial No. 161,770. (No model.)

To all whom it may concern:

Be it known that I, THOMAS G. NEWNAM, a citizen of the United States, residing at Holden, in the county of Johnson and State of Missouri, 5 have invented a new and useful Washing-Machine, of which the following is a specification.

This invention has relation to improvements in washing-machines; and it consists in the construction, novel arrangement, and adaptation of devices, as will be hereinafter more fully set forth, and particularly pointed out in the claims appended.

In the accompanying drawings, Figure 1 is a transverse vertical sectional view taken 15 through the heads of the clothes-holder. Fig. 2 is a side elevation, and Figs. 3 and 4 are interior views of the clothes-holding cylinder.

In the accompanying drawings, A indicates a base, from which rise at a suitable interval 20 two standards, a a', for supporting a rotary cylinder or other suitable clothes-receptacle, as will be presently explained.

B indicates the clothes and suds holder, which is illustrated in cylindrical form, but 25 may be of rectangular or other suitable shape. This cylinder is open at one end, and provided with a removable cover, b. This cover is provided centrally on its outer side with a fixed journal, C, which is provided at its outer end 30 with a crank-arm, D, the journal having its bearing in an open slot at the upper end of the fixed standard a. The opposite end, b', of the cylinder is fixed to the body portion thereof, and is provided on its outer side with a central horizontal fixed journal, e, which has its bearing in the upper end of the hinged section b' of the standard a'. Adjacent to this hinged standard, and on a level, or nearly so, with the upper edge of the lower or rigid section of the 35 same, is arranged a frame, E, the object being to afford a support for the clothes-holding cylinder when raised from the standard a and turned laterally outward, so as to rest upon the closed end thereof. The upper edges of this 40 frame may be recessed, as shown at e, for the reception of the hinged section b' of the standard a' when turned outward. The cylinder is provided on its outer or convex sides with straps d, for securing the cover in position with 45 relation to the said cylinder. These straps are formed in two sections, which are hinged

together at their adjacent ends, and provided at their outer ends with flanges or short arms f f', the sections having the arms f being secured to the cylinder body with the said arm 55 engaging the end b thereof, and the arm f' of the hinged section is designed to engage the removable cover, having perforations for the reception of set-screws, as shown, to secure the said cover in position upon the open end 60 of the cylinder.

When the cover is made of wood or other similar material, it is desirable to protect the same from injury by the set-screws in the fastening-strap, and therefore I provide the cover 65 in such cases with metallic strips g at the points of engagement with the said screws. These strips may conform to the outer edges of the cylinder, and be of any suitable form on their inner edges.

F F indicate cones, which are arranged in fixed position on the central inner side of the wall b' of the cylinder and cover, respectively, having their apexes oppositely directed. These cones are designed during the operation of the 75 machine to prevent the clothes therein from clustering around the brushes and consequently the axis of rotation of the cylinder. It will be seen that these cones, arranged in this position, will tend to throw the clothes from the 80 axial center of the cylinder and in contact with the cleansing-brushes. The cones may be provided at their base with apertures h, and at their apex with an aperture, to permit the free circulation of water through them and upon 85 the clothes.

The inner or concave walls of the cylinder are provided at suitable intervals with horizontal brushes G, which are fixed in position by means of screws or other suitable fastening 90 devices.

H indicates a horizontal rod, which is secured to the outer side of the cylinder at any suitable point thereon and forward of the edges of the open end thereof. The cover is provided on its periphery with an eye or loop, I, for the passage of the said rod H. This rod is designed to serve the double function of preventing the cover from turning upon the cylinder, and as a hinge for the said cover when 100 it is not desirable to entirely remove the same. The cover may be provided with an aperture

having a screw-cap, for the purpose of letting out the suds or letting in fresh water to the cylinder. The journal extending from the outer side of the cover is provided with two 5 annular vertical flanges, *i i*, to extend on opposite sides of the standard *a*, to prevent any unnecessary vibratory movement of the cylinder during operation.

What I claim is—

- 10 1. In a washing-machine, a rotary cylinder having its inner vertical walls provided with central oppositely-directed cones, each having an opening at its apex and an opening at its

base, whereby a circulation of water through the said cones may be obtained, substantially 15 as specified.

2. In a washing-machine, a rotary horizontal cylinder having its vertical walls provided with axial cones and radially-arranged brushes, each of said cones having an opening at its 20 apex and an opening at its base, substantially as specified.

THOMAS G. NEWNAM.

WILLIAM D. PATTERSON,
JOSEPH U. STRODE.

Correction in Letters Patent No. 328,801.

It is hereby certified that Letters Patent No. 328,801, granted October 20, 1885, upon the application of Thomas G. Newnam, of Holden, Missouri, for an improvement in "Washing-Machines," was erroneously issued to said Newnam; that said Letters Patent should have been issued to *Thomas G. Newnam and Frederick Heberling*, said Heberling being assignee of one-half interest; and that the said Letters Patent should be read with this correction therein that the same may conform to the record of the case in the Patent Office.

Signed, countersigned, and sealed this 10th day of November, A. D. 1885.

[SEAL.]

H. L. MULDROW,
Acting Secretary of the Interior.

Countersigned:

M. V. MONTGOMERY,
Commissioner of Patents.
